UNITED STATES PATENT OFFICE

JAY M. AXTELL, OF FORT WORTH, TEXAS

WORKING HEAD FOR WINDMILLS, PUMP JACKS, AND THE LIKE

Application filed April 1, 1930. Serial No. 440,680.

My invention relates to working heads for windmills, pump jacks and the like; and the object is to provide simple and economic construction of devices for use as windmills, 5 pump jacks, and the like and to provide the construction and devices with automatic lubricating means. The advantage of the improved construction is that it is simple and compact and easily installed and easily operated. Another advantage, a center lift of the 10 load is obtained. Other objects and advantages will be fully explained in the following description and the invention will be more particularly pointed out in the claims.

Reference is had to the accompanying drawings which form a part of this application.

Fig. 1 is a vertical section of a working head for the windmill and pump construction, showing an end view.

Fig. 2 is a horizontal section of the same.

Fig. 3 is a vertical section of the housing, showing the driving mechanism.

Fig. 4 is a horizontal section of the means 25 fastening the crank shaft to the gear.

Similar characters of reference are used to indicate the same parts throughout the several views.

The pump head is provided with a housing 30 in two parts,—the upper part 1 cooperating with the lower part 2 which forms the lubricating reservoir and both parts inclosing the operating parts. The main driving shaft 3 is journaled in bearings 4 and 5. The bearing 4 is held in place by the cap 6 which is attached to the horizontal reservoir housing 7 by means of screw bolts 8. The bearing 5 is held in place by the cap 9 which is attached to the housing member 2, and by screw bolts 40 10.

A pinion 11 is rigid with shaft 3 and is driven by this shaft. The pinion 11 drives the cog wheel 12 which is rigid with the crank shaft 13, shown in Fig. 4. The crank shaft 45 13 is journaled in bearings 14 which are attached to housing member 2. See Figs. 2 and 3. The bearings 14 are held in place by caps 15. The shaft 13 actuates the piston rod 16. Pitman bar 17 engages the crank shaft 13 50 and is pivotally connected to a driving or

cross head 18 by a pivot bolt 19 which is carried in a bearing 20 which is integral with the pitman bar 17. The driving head 18 engages both ends of the bolt 19. The driving or cross head 18 is rigid with the piston rod 55 16. A guide bearing is provided for the piston rod 16. A boss 21 is formed on the housing 1 and a guide bearing 22 is mounted for the piston in the holder or boss 21. A housing 23 incloses the upper end of the piston rod 60 16 and holds bearing 22 in place.

Provision is made for automatically lubricating the working parts of the windmill. A reservoir 24 is formed in the top of the driving head 18 for lubricating the piston rod 16 65 and the bearing 22. As the piston rod 16 is reciprocated vertically, the reservoir 24 delivers lubricant to the bearing 22. The bearing is long enough to dip into the reservoir 24 on the extreme upstroke of the piston rod 70 16. The driving head 18 has a lubricant distributor 25 formed integral therewith. The distributor 25 delivers lubricant to the bearing 20, to the crank arm 26 and to the shaft 3. Lubricant is automatically supplied to the 75 distributor 25 by a displacement, force feed oiler consisting of a pipe 27 which is carried by the distributor 25 and operates in a cylinder 28. A piston head 29 is carried by the pipe 27. On the downward stroke of the head 18, the head 29 of the pipe 27 will compress the lubricant in the cylinder 28 and force the lubricant in the cylinder 28 up the pipe 27 and into the distributor 25. This operation takes place on every downward 80 drive or stroke of the head 18 and the piston rod 16. A supply of lubricant is maintained in the lower part 2 of the housing which serves as a reservoir of the lubricant. Oil or 85 other lubricant is let into the cylinder 28 through perforations 30 therein, from the part 2 of the housing. The working parts above described are kept constantly lubricated in this manner.

The lubricant is prevented from entering 90 the well casing 31. The head 18 has a flared skirt 32 and a tube 33 surrounds a portion of the piston rod 16 and is inserted in the housing frame member 34. In this manner no lubricant can pass from the housing 2 into 100

the casing 31 and the skirt or shield 32 prevents lubricant from entering the pipe 33.

What I claim, is,—

1. A working head for windmills, pump jacks, and the like, comprising a housing in upper and lower parts, a driving shaft and a crank shaft journaled in said lower part, gearing actuated by said driving shaft for driving said crank shaft, said lower part of said housing serving as a lubricant reservoir, a piston rod adapted to move vertically in said housing, a guide bearing for said piston rod, a driving head rigid with said piston rod and actuated by said crank shaft, a lubricant distributor carried by said driving head for delivering lubricant to said guide bearing and to the working parts of said working head, and means actuated by said distributor for delivering lubricant from said reservoir to said distributor.
2. A working head for windmills, pump jacks and the like comprising a housing in upper and lower parts, a guide bearing rigid with said upper part and projecting within the housing, a protecting cap rigid with said housing for a piston rod, a piston rod movable vertically in said housing and in said cap, means for operating said piston rod, a distributor rigid with said piston rod and provided with a cavity in its upper face, said lower part of the housing constituting an oil reservoir, a cylinder projecting down in said reservoir and made stationary therewith, a hollow plunger rod carried by said distributor and projecting down in said stationary cylinder and carrying a hollow plunger, said cylinder having intake ports and said rod forcing oil upwardly into said distributor when said plunger is forced below said ports, and means for preventing oil from following said piston rod down into a well.
3. A working head for windmills, pump jacks, and the like comprising a housing in upper and lower parts, the latter forming an oil reservoir, a guide bearing rigid with said upper housing and constituting in part means for lubricating a piston rod, a piston rod moving vertically in said housing and through said guide into said cap, means for actuating said piston rod, a distributor rigid with said piston rod and provided with a cavity in its upper face for supplying oil to said guide, means actuated by said distributor for supplying oil thereto, and means for preventing oil from following said piston rod down into the well consisting of an upstanding tubular pipe rigid with said lower housing and projecting above the oil in said reservoir and a shield carried by said rod to prevent oil from entering said upstanding pipe.

In testimony whereof, I set my hand, this 21st day of March, 1930.

JAY M. AXTELL.
